UNITED STATES PATENT OFFICE

JOHN D. RENSHLER, OF FINDLAY, OHIO

AUTOMATIC LOCKING AND FASTENING DEVICE FOR VAULTS

Application filed May 19, 1931. Serial No. 538,511.

This invention relates to locking devices and more particularly to means for locking a cover about a coffin or the like.

An object of this invention is to provide locking means for locking a cover about a coffin so as to provide an air sealed chamber within which the coffin is disposed.

Another object of this invention is to provide in a device of this kind means for locking the cover on the base of the device and simultaneously securing the article disposed therein against movement.

A further object of this invention is to provide in a device of this kind means by which the closure may be opened or closed from a point disposed at one end of the device.

A still further object of this invention is to provide means for releasably holding the locking member in locked position so that it will not readily become unlocked during the movement of the device.

The above and various other objects and advantages of this invention will in part be described in and in part be understood from the following detailed description of the present preferred embodiment, the same being illustrated in the accompanying drawings, wherein:—

Figure 1 is a detail side elevation of a vault having a device constructed according to the preferred embodiment of this invention mounted therein;

Figure 2 is an enlarged sectional view partly in detail of the base showing the securing pin for securing an article on the base, and

Figure 3 is a fragmentary bottom plan view of the base and showing in detail the invention hereinafter described.

Referring to the drawings wherein like numerals of reference designate corresponding parts throughout the several views, the numeral 10 designates generally the base of a cover or vault for a coffin, the base 10 comprising a flat upper portion 11 having downwardly disposed sides 12 and end members 13 and 14, the end 13 comprising the rear end of the device, whereas the end 14 comprises the front end. A cover or vault member 15 is hingedly secured at one end thereof to the

base plate 11 at the rear end 13 thereof by means of conventional hinges or the like.

In order to securely lock the cover 15 on the base 10, I have provided a locking structure, generally designated as 16, which is disposed within the base 10 and engages the cover 15, so as to releasably seal the cover 15 on the base 10. This locking structure 16 comprises a pair of locking members 17 which are pivotally mounted on a bracket 18 carried by the base 10 adjacent each side wall 12 thereof and adjacent the forward end 14. The side walls 12 are provided with elongated slots or openings 19 through which one end of each locking member 17 is adapted to be projected for engagement in a notch or recess 20 disposed in the side walls of the cover or vault member 15.

An operating lever 21 of substantially L-shaped construction is pivotally mounted on the lower surface of the front wall 14 by means of a pivotal member 22, one end of the lever 21 constituting a handle for rocking the lever and the opposite leg is provided with suitable apertures for receiving connecting links 23 which connect the locking members 17 with the inwardly extending leg 24 of the operating lever 21. These links 23 are so connected that movement of the leg 24 in one direction will swing both of the locking members 17 inwardly into released position, and movement in the opposite direction will swing the locking member 17 outwardly so as to engage in the recesses or keepers 20 carried by the cover 15.

A pair of centrally disposed locking members 25 are mounted in the side wall members 12 at a point substantially centrally of the length of the side walls 12 and are adapted to be projected through slots 26 in the side walls 12 for engagement in keepers or notches 27 disposed in the side walls of the cover 15. These central locking members 25 are connected to the forward locking member 17 by means of connecting links 28 so that when the forward locking members 17 are rocked into either locking or released position, the central locking members 25 will be likewise locked into the same relative position.

A spring pressed lever engaging member 29 is mounted in the front wall 14 and engages in a detent 30 in the lever 21, so as to hold the lever 21 in locked position. The 5 forward leg of the locking lever 21 is disposed in substantial alinement with the wall 14.

In order to secure an article on the top of the plate or base 10, I have provided a locking pin 31 which is secured to a rockable lever 32 mounted on a bracket 33 which is secured to the lower surface of the plate 11. This locking or securing pin 31 is adapted to be projected through a slot 34 in the base plate 11 and to extend upwardly from the upper surface thereof so as to engage the bottom of a coffin or article disposed on the top of the plate 11.

In order to rock the lever 32 coactive with the rocking of the locking members 17 and 25, the lever 32 is connected to one of the locking members 17 by means of a connecting link 35. In this manner, when the cover or vault 15 is lowered into closed position 25 about the base 10, the rocking of the operating lever 21 will not only lock the cover 15 on the base 10, but will simultaneously lock or secure a coffin on the top of the base plate 11, so that movement of the vault structure 30 will not cause the coffin disposed therein to move either laterally or longitudinally.

In the operation of this device, the locking members 17 and 25, when in released position, are disposed inwardly of the side walls 12 and out of engagement with the notches 20 and 27, respectively, of the vault member 15. In this position, the operating member 21 is disposed with one leg thereof outwardly of the front wall 14 and the locking pin 31 is disposed within the hollow base 10, so that it will not interfere with the insertion or the removal of the coffin from within the vault 15. When it is desired to lock the vault 15 and to secure the coffin disposed therein against movement, both lateral and longitudinal, the operating lever 21 may be moved inwardly toward the front wall 14, this movement rocking the inwardly extending leg 24 which coactively rocks the locking members 17 and 25 into locking position, so that the outer ends thereof will be disposed in the keepers 20 and 27, respectively.

It will be obvious, from the foregoing, that a relatively simple locking means has been provided for releasably locking the cover of an air sealed vault.

As shown in the drawings, the lid or cover 15 is adapted to be held in upraised or open position by means of a brace member 36 which is pivotally secured at one end to the base structure 10.

It is, of course, understood that various changes and modifications may be made in the details of construction and design of the 65 above specifically described embodiment of

this invention without departing from the spirit thereof, such changes and modifications being restricted only by the scope of the following claims.

I claim:

1. A locking and fastening device of the character described comprising in combination with a vault including a base and a cover, a plurality of locking members, means for pivotally mounting said locking members on the base, said base having openings therethrough whereby to permit the projection of the locking members through the base, said cover having registering openings adapted to receive the projected ends of the locking members, operating means for said locking members, means for pivotally mounting said operating means on a marginal edge of said base, a fastening member, means for pivotally mounting said fastening member on the base, said base having an opening therethrough whereby to permit the projection of the fastening member upwardly therethrough, and connecting means whereby to permit the rocking of said fastening member 70 coactive with the rocking of said locking members.

2. In a vault construction including a base and a cover, horizontally swingable locking means carried by the base and adapted to engage the cover for releasably locking the cover on the base, a vertically movable fastening member carried by the base and adapted to be projected upwardly therethrough whereby to engage an article disposed on the base 85 and to hold said article against horizontal movement, and connecting means connecting said fastening member with said locking means for simultaneous operation thereby.

3. In a vault construction including a base and a cover, horizontally swingable locking means carried by the base and adapted to engage the cover for locking thereof and a vertically movable article holding member carried by the base and adapted to hold an article disposed on the upper surface of the base against movement, said holding member comprising a securing pin, a bracket mounted on the base, means for pivotally securing said pin on said bracket, said base having an opening whereby to permit the pin to be projected therethrough, and connecting means connecting said pin with said locking means for simultaneous operation thereby.

4. In combination, a base member, a member engaging the marginal edges of the base and a second member engaging the upper surface of the base, horizontally swingable locking means carried by the base and projectible through the marginal edges of the base for locking the first member on the base and a second locking member carried by the base and projectible through the upper surface of the base whereby to engage said second member, connecting means connecting 120 125 130

said first locking means with said second locking means, and operating means whereby to simultaneously move said first and said second locking means into locking or released position.

5 In testimony whereof I hereunto affix my signature.

JOHN D. RENSHLER.
